(57) **CLAIM**

The ornamental design for a vehicle seat, as shown and described.

DESCRIPTION

FIG. 1 is a perspective view of a first embodiment of the vehicle seat;

FIG. 2 is a front elevational view of the seat of FIG. 1;

FIG. 3 is a rear elevational view of the seat of FIG. 1;

FIG. 4 is a side elevational view of the seat of FIG. 1;

FIG. 5 is a perspective view of a second embodiment of the vehicle seat;

FIG. 6 is a front elevational view of the seat of FIG. 5;

FIG. 7 is a rear elevational view of the seat of FIG. 5; and, FIG. 8 is side elevational view of the seat of FIG. 5.

The broken lines showing the center portions of the back and bottom sections of the seat in the first embodiment and the broken lines showing a button on the side of the seat in both embodiments are for illustrative purposes only and form no part of the claimed design.
